UNITED STATES PATENT OFFICE.

FRANK L. HARMON, OF BEVERLY, MASSACHUSETTS, ASSIGNOR TO UNITED SHOE MACHINERY COMPANY, OF PATERSON, NEW JERSEY, A CORPORATION OF NEW JERSEY.

SKIVING-MACHINE.

1,161,860.

Specification of Letters Patent. Patented Nov. 30, 1915.

Application filed March 9, 1911. Serial No. 613,318.

To all whom it may concern:

Be it known that I, FRANK L. HARMON, a citizen of the United States, residing at Beverly, in the county of Essex and State of Massachusetts, have invented certain Improvements in Skiving-Machines, of which the following description, in connection with the accompanying drawings, is a specification, like reference characters on the drawings indicating like parts in the several figures.

This invention relates to skiving machines and is herein shown as embodied in a machine of the type disclosed in United States Patent No. 726,285 which was granted to me on April 28, 1903.

In practice it is required, in order to meet various conditions, that means be provided for varying the width, angle and character of the skive produced on the stock, these skives being commonly known as "straight" and "shoulder." Hitherto the angle of the skive has been varied by adjusting some part of the machine, for example the knife, while the change from a straight to a shoulder skive or vice versa has necessitated the replacement of the feed roll by another roll of the proper contour. In the present invention such adjustments and replacements are done away with by providing, with a feed roll which is yieldable bodily and angularly, a plurality of interchangeable presser feet the working faces of which are formed to produce the various types of skives. These presser feet are adapted to be readily attached and detached, and are carefully fitted and adjusted to the machine in the shop where the machines are manufactured so that thereafter when said machines are in use no skill on the part of the operator is required to change from one type of skive to another.

Another object of this invention consists in the provision with a combined stock supporting and roll supporting member, of means for producing relative movement between the knife and said member; and preferably the edge gage and presser foot are also mounted upon this member. In the illustrated embodiment the supporting member is made adjustable so that when the knife becomes worn the single adjustment of this member brings the roll and knife into proper relative position without neces-

sitating any adjustment of the edge gage or presser foot.

It is desirable that the forward portion of the edge gage be maintained in close proximity to the knife edge. When a knife having a circular outline is used, however, lateral adjustment of the edge gage increases the space between said gage and said knife so that a second adjustment is required to bring said gage up to proper position.

In order to overcome this disadvantage a further object of this invention consists in the provision with a knife having a circular outline of an edge gage which when adjusted is compelled to move in a curved path corresponding to the curve of the knife edge. With this construction the distance between the edge gage and the knife edge remains the same whatever the lateral position of said gage.

In machines wherein the contour of the presser foot or its angular adjustment determines the contour of the skive it sometimes happens that the stock buckles between the presser foot and the knife and is not properly smoothed out. Or it may be that although no buckling occurs the stock is not fed with the desired speed.

Accordingly another object of this invention consists in the provision of a spring pressed auxiliary roll to coöperate with the feed roll; and preferably this auxiliary roll is positively driven, and the tension of the spring which presses it against the stock may be varied. With this construction the rate of feed may be controlled and the leather smoothed out as it is fed to the knife.

These and other features of the invention including certain details of construction and combinations of parts will be explained in connection with the following description of a machine and will be pointed out in the claims.

Referring to the accompanying drawings, Figure 1 is a side elevation; Fig. 2 is a section on the line 2—2 of Fig. 3; Fig. 3 is a section on line 3—3 of Fig. 2; Fig. 4 is a perspective of the feeding and cutting mechanism taken from above the supporting table; Fig. 5 is a perspective of the feed roll and its mounting taken from below said table, and Fig. 6 is a perspective of a presser foot.

Mounted in alined bearings in the frame 1 is an upright shaft 3, said shaft carrying a worm 5. Fast to said shaft is also a driving pulley 9; and a belt 11 passes around said pulley and over two guide pulleys, one of which is shown at 13, said belt being driven from any suitable source of power.

Mounted upon and having connection with the frame 1 by means of a slide bearing 10 is a supporting member or table 15. In order that the table may be adjusted when desired, a thumb screw 17 is rotatively mounted in a lug 19 depending from said table and is screw-threaded into the frame, said screw being held from longitudinal movement with respect to said lug as shown. This adjustable table carries the feeding mechanism, the edge gage and the presser foot so that if at any time the knife 20 becomes worn it is necessary merely to turn the thumb screw 17, whereupon the feeding mechanism, edge gage and presser foot will be simultaneously adjusted without destroying their relation to one another.

25 In the illustrated machine the different angles of bevel are produced by the use of interchangeable presser feet, the roll being adapted to yield bodily from the knife in order to permit the passage of skivings of 30 different thickness and to yield angularly to accommodate its position to the production of bevels of different angles. Depending from the under side of the table are two lugs 21 and 23, and threaded through said lugs are two pivot screws 25. Held between the conical ends of said screws is a block 27, said block having fastened to its under side by means of screws 29 a plate 31; and in order to support said plate yieldingly a coiled 35 spring 33 carried by an upright rod 35 and adjustable as to tension by means of a nut 37 bears against the under side of said plate to one side of a line passing through the alined axes of the screws 25, while upward movement of said plate is limited by an adjustable stop 39 threaded through a plate 40 which is fast to the supporting member or table 15. In a socket in the block 27 fits a tubular extension 41 of a yoke 43, said extension being internally screw-threaded to 45 receive a pivot screw 45. This yoke 43 carries near the extremities of its arms the feed roll shaft 47. Attention is here directed to the fact that this yoke 43 is not symmetrical, one arm being a thin straight extension of the base and extending into the narrow 50 space between the feed roll 71 and the auxiliary roll 137, said extension being enlarged to form a bearing for the inner end of the feed roll shaft, as best shown in Fig. 3, while the end of the other arm of the yoke 55 forms a bearing for the outer end of the feed roll shaft, as best shown in Fig. 5. And the pivot screw 45 is so located that its axis 60 if extended would pass through approxi-

mately the extreme upper left hand portion of the feed roll 71 as viewed in Fig. 3. It will thus be clear that the upper left hand point of said roll will remain in a substantially fixed position when said roll is tilted. 70

The shaft of the feed roll 71 is connected with its driving member 49 by means of a cap 59 and a universal coupling comprising a rod provided at each end with spherical portions 53 in which are fixed pins 55 and 57. In order to support the outer or right hand end of the feed roll shaft a spring 61 bearing upwardly upon the yoke 43 is fastened to a block on the under side of the table by means of a screw 63, a thumb-screw 65 being provided to regulate the tension of said spring, said thumb-screw having an enlarged portion to contact with the under side of said spring and having its upper end threaded into the table 15. In order 75 to limit the upward movement of the outer or right hand end of the feed roll shaft, an adjustable stop 67 in the form of a headless screw is provided, said screw contacting with a plate 69 fast to the supporting table. 80 It will appear from the construction thus far described that the feed roll 71 is bodily movable toward and from the under side of the knife about the axis of the screws 25 and is also angularly movable about the axis of the screw 45, the extended axis of this screw passing approximately through the upper left hand or inner end of the feed roll. 85

90 As has been stated above the character of the bevel produced by the present machine is determined by the contour of the working face of the presser foot, and in order to adapt the machine to the production of skives of different character a plurality of 95 interchangeable presser feet are provided. In Fig. 4 one of these feet is shown in position at 72, said foot comprising a base having in its under side two sockets to fit over two guide pins, one of which is shown at 73. In order to hold the presser foot firmly in place a clamping member comprising a handle 75, a rotatable shank 77 and a cross-piece 79 is provided, said cross-piece having its under side slightly beveled so that in the 100 position shown in Fig. 4 the presser foot is held firmly in place. The shank 77 is rotatable in the table 15 but is held from longitudinal movement, while a slot 81 in the presser foot permits the removal and replacement of said foot when the cross-piece 105 has been rotated to suitable position. In order to permit the inclination of the presser foot to be varied when desired, a set screw 83 is threaded through said foot and abuts the table beneath, a locking member 85 being provided to hold said screw in adjusted position. Ordinarily the set screw on each 110 presser foot is adjusted to and locked in proper position at the machine shop so that when the machine is sent out into regular 115

120

125

130

use the operator in order to produce a skive of the angle or character desired has only to select the proper presser foot and lock said foot in place by means of the handle 75.

In Fig. 6 another presser foot 195 is shown, said foot being detached from the machine; and it should be noted that the working face 197 differs from that of the foot 72. This presser foot is provided with a set screw 199 which has been properly adjusted so that the foot is ready to be clamped in place when desired.

In machines of this class it is usual to provide an edge gage to guide the edge of the stock as it is being skived, and commonly these gages are made adjustable in a straight line. In the present invention, however, the edge gage is so mounted that as it is adjusted it moves in a curved path, its forward end thus following the contour of the edge of the knife. The construction by which this is accomplished in the illustrated embodiment is as follows:—Slidably mounted upon the yoke 43 is a member 87 having a straight slot 89; and pivoted at 92 upon said member is a second member 91 having a curved slot 93. In order to hold said members in adjusted position a clamping member 95 is provided, said member being engaged by a thumb-screw 97. The edge gage 99 is shown as formed integral with the member 91. The shank of the thumb-screw 97 passes through a bore in the yoke 43 its axis being thus stationary with respect to the gage; and the pivot 92 holds the members 91 and 87 so that they are compelled to move together when one is adjusted. It will now be clear that, when the thumb-screw 97 is loosened and the member 87 moved longitudinally, the member 91 because of its curved slot 93 and its pivotal connection 92 will be moved in a curved path and will carry with it the edge gage 99. The form of this edge gage is best shown in Fig. 2 wherein it will be seen that the end of said gage is cut away to fit the presser foot 72 and that the innermost portion of said gage extends beneath said foot in close proximity to the edge of the knife. With this construction and mounting of the gage it will be clear that in all its positions its end is automatically kept close to the edge of the knife.

Turning now to the mechanism for driving the feed roll the driving sleeve 49 is supported in a block 101 fastened by screws, not shown, to the table 15, and said sleeve is held from longitudinal movement with respect to said block by means of a yoke 105 fitting in a groove in said sleeve and held fast to said block by a screw 107. This sleeve 49 is formed at one end with a gear 111, and this gear meshes with an idle gear 113 which rotates upon a stud 115 carried by the frame. Meshing with the idler 113 is

a second idler 117 also carried by the frame, said second idler being driven from a gear 119 fast upon a counter-shaft 121; and this counter shaft is driven from the worm 5 by means of a gear 123. The gears 111 and 113 are so arranged that when the table 15 is adjusted the gear 111 may roll on the gear 113, no adjustment of any of the gears between the worm 5 and the feed roll being necessary.

The knife 125, of the rotary type, is provided with a circular opening at its center which fits over a cylindrical extension of the enlarged upper end of the shaft 3 and is clamped to said enlargement by a screw 127; and in order to insure that said knife shall be held from turning with respect to said shaft, a pin 129 fixed in the enlarged end of said shaft extends up through a suitable hole in said knife. The knife shaft rotates at a high speed, and in order to provide continuous and efficient lubrication a pocket 133 is formed in the upper part of the frame, and said pocket is packed with an absorbent material 135 such as felt. Access to this pocket is permitted by a shallow channel which is cut in the upper surface of the frame, said channel being covered by a plate 130. In the present machine the skivings pass beneath the knife, and in order that they may not clog the gears or otherwise interfere with the operation of the machine the frame of the machine adjacent the feed roll is cut away in a curve, and a chip chute 131 is attached thereto by any suitable means.

In order to insure that the work shall be fed rapidly and uniformly to the machine an auxiliary feeding mechanism is provided. Fast to the sleeve 49 which drives the feed roll is a roll 137, and coöperating with said roll 137 is an auxiliary roll 139. This auxiliary roll is carried by a flexible shaft 141. One end of this shaft is journaled in a block 143 which is fast to the table 15 while the other end is journaled in a block 145 which is shown as integral with a spring arm 147. In order that the tension of this spring arm may be varied said arm rests upon a wedge shaped piece 149, a screw 151 passing through said arm and piece and holding them fast to the block 143 as shown. A thumb-screw 153 also passes through these members and into the block, said screw being located near the thinner end of the wedge-shaped piece 149. A set screw 155, provided with a lock nut 157, is threaded through said spring arm and abuts the upper surface of the block 143. With this construction and arrangement of parts the tension of the spring arm may be varied by turning the thumb-screw 153, and by adjusting the set screw 155 the position of the roll 139 and hence the distance between that roll and the roll 137 may be varied. The 180

members 71 and 137 have for convenience been described as two separate rolls but it is clear that they may be regarded with equal correctness as parts of a single roll, one of said parts being yieldingly supported.

The shaft 159 which carries fast to its upper end the grinder 161 is rotatably mounted in alined bearings in a carrier 163, said carrier being cut away between said 10 bearings to provide space for the pulley 165 fast on the grinder shaft. The upper and lower bearings of the carrier are connected by a member 167 which is hollow to provide an oil reservoir, a cap 169 closing the upper 15 end thereof. This carrier 163 is fast to a shaft 171 which is rotatable in bearings in the frame. Fast to the opposite end of this shaft is an arm 173, and threaded through this arm is an adjusting screw 175, said screw 20 being mounted in a lug 177 extending horizontally from an upright boss 179, a pair of collars on said screw holding it from longitudinal movement. The bearings for the grinder shaft are provided with oil wells 25 packed with felt similar to that provided for the knife shaft. The oil hole for the upper bearing is closed by a knurled ring 181, while that for the lower bearing, as has been stated is closed by the cap 169. It should be noted 30 that the pulley 165 of the grinder shaft is so located that it is driven from the belt 11 which also drives the knife and the feeding mechanism. In order to remove any bur 35 which may be formed on the under side of the knife edge an auxiliary stationary grinder 183 is carried by the table.

The flexible shaft 141 is driven from the shaft 121 by means of pulleys 185 and 187 and a belt 189. In order to keep said belt 40 tight a tightener pulley 191 is mounted on a stud which is carried by an adjustable bracket fastened to the under side of the table. With this construction the belt 189 may always be kept tightened whatever may 45 be the adjusted position of the table.

In operation the stock is placed on the supporting table and fed to the rolls. The rigid presser foot forces the feed roll to yield bodily and angularly so that the stock 50 is presented to the knife in a manner dependent upon the contour of the working face of said presser foot. The stock passes over the knife while the skivings pass beneath the knife and are directed away from 55 the working parts by the chute 131. When it is desired to change the character of the skive the presser foot is replaced by one having a working face of proper contour.

Although the invention has been set forth 60 in connection with a particular machine it should be understood that nothing herein contained is to be construed as limiting the invention in the scope of its application to the particular machine shown and described.

Having thus described the invention what

I claim and desire to secure by Letters Patent is:—

1. A machine of the class described having, in combination, a shaft, a knife fixed to the upper end thereof, means for rotating said shaft, a feed roll, and a train of gears connecting said roll and shaft whereby said roll is driven from said shaft, said train comprising a gear held to rotate with said roll and an adjacent gear, said gears being placed one above the other whereby the feed roll may be horizontally adjusted while maintaining the mesh of said gears. 70

2. A machine of the class described having, in combination, a shaft, a knife mounted on the upper end thereof, a feed roll, a work table carrying said roll, means for actuating said shaft and roll, means for yieldingly supporting said roll against movement toward and from said knife and against angular movement with respect to said knife, and a rigidly held presser foot whereby the contour of the acting face of said foot determines the character of the skive produced. 80

3. A machine of the class described having, in combination, a knife, a feed roll, a supporting member carrying said roll, said member being adjustable toward and from said knife, means for actuating said knife and roll, said roll being yieldingly mounted 95 to accommodate different thicknesses of stock and different angles of bevel, and a rigidly held presser foot.

4. A machine of the class described having, in combination, a shaft, a knife mounted upon the upper end thereof, means for actuating said shaft, a pivoted supporting block, a yielding member acting to rotate said block about its pivot, a yoke pivotally mounted in said block, a yielding member acting to rotate said yoke about its pivot, a feed roll mounted in said yoke, means including a universal joint for actuating said roll, and a rigid presser foot. 100

5. A machine of the class described having, in combination, a knife, means for actuating said knife, a feed roll, a longitudinally adjustable member carrying said roll, said roll being bodily movable about an axis approximately parallel to its own and being also angularly movable about an axis at right angles to its own, said last named axis intersecting said roll at approximately its uppermost, innermost point, a rigidly held presser foot, and means for actuating said roll. 110

6. A machine of the class described having, in combination, a knife having a circular outline, a feed roll, means for actuating said knife and roll, a presser foot, an adjustable edge gage, and means connected with said gage for automatically compelling the adjustment of said gage to take place in a curved path corresponding to the curve of the knife edge. 125

7. A machine of the class described having, in combination, a knife, a feed roll, means for actuating said knife and roll, a presser foot, a longitudinally adjustable member having a straight slot, a second adjustable member having a curved slot, a pivot connecting said members, a pin extending through both slots, said pin being held from movement in the direction of adjustment of said members, and an edge gage carried by said second adjustable member.

8. A machine of the class described having, in combination, a knife, a yielding feed roll, an unyielding auxiliary roll coaxial with said feed roll, means for actuating said rolls and a spring pressed roll coöperating with said unyielding roll.

9. A machine of the class described having, in combination, a knife, a yielding feed roll, an unyielding auxiliary roll coaxial with said feed roll, means for actuating said rolls, a spring pressed roll coöperating with said unyielding roll and means for varying the pressure exerted by said spring-pressed roll.

10. A machine of the class described having, in combination, a knife, a table, means whereby the table may be adjusted toward and from said knife to compensate for wear of the knife, a feed roll and an auxiliary roll carried by said table, and means for actuating said rolls.

11. A machine of the class described having, in combination, a knife, a feed roll, a pair of coöperating auxiliary rolls situated at one end of said feed roll, one of said auxiliary rolls being coaxial with said feed roll, and means for actuating said knife, feed roll and auxiliary rolls.

12. A machine of the class described having, in combination, a rotary shaft, a knife mounted on the upper end of said shaft, means for actuating said knife, a supporting member, a carrier supported thereby, said carrier being mounted to yield bodily and angularly, a feed roll mounted in said carrier, an edge gage mounted on said carrier, a rigid presser foot, and means for actuating said roll.

13. A machine of the class described having, in combination, a rotary shaft, a knife fixed to the upper end thereof, a feed roll arranged to act upon the under side of the stock, means for actuating said roll from said knife shaft, and an auxiliary spring-pressed roll arranged to act upon the upper side of the stock.

In testimony whereof I have signed my name to this specification in the presence of two subscribing witnesses.

FRANK L. HARMON.
